(57) **CLAIM**

The ornamental design for a beverage dispensing machine, substantially as shown and described.

DESCRIPTION

FIG. 1 is a front perspective view of a beverage dispensing machine.

FIG. 2 is a bottom view of the beverage dispensing machine of FIG. 1.

FIG. 3 is a top view of the beverage dispensing machine of FIG. 1.

FIG. 4 is a right-side view of the beverage dispensing machine of FIG. 1.

FIG. 5 is a left-side view of the beverage dispensing machine of FIG. 1.

FIG. 6 is a front view of the beverage dispensing machine of FIG. 1; and,

FIG. 7 is a rear view of the beverage dispensing machine of FIG. 1.

The broken lines show portions of the beverage dispensing machine that form no part of the claimed design.
